HAT BLOCK

Filed June 6, 1928

Fig. 1.

A. Jiménez Inventor

By Lacy, Lacy, Attorney.

UNITED STATES PATENT OFFICE.

AGUSTIN JIMÉNEZ, OF NEW YORK, N. Y.

HAT BLOCK.

Application filed June 6, 1928. Serial No. 283,294.

This invention relates to a hat block and more particularly to a hat block upon which a lady's hat may be placed and supported while it is being trimmed.

5 One object of the invention is to provide a hat block formed of sections movable toward and away from each other so that the block may be adjusted according to the size of hat to be trimmed and to provide an improved type of frame carrying the sections of the block and adjustable so that the sections may be retained in set positions.

Another object of the invention is to provide a frame which may be securely connected 15 with the companion block forming sections and serve not only as means to carry the sections but also so construct the frame that it may be rotatably mounted upon a stem or spindle and thereby allow the block and a hat 20 carried thereby to be turned while trimming the hat.

Another object of the invention is to yieldably resist movement of the block forming sections toward each other so that they 25 may be easily separated and to provide improved means to mount springs which urge the block forming sections away from each other.

The invention is illustrated in the accompanying drawing, wherein

Figure 1 is a view showing the improved hat block partially in longitudinal section and partially in elevation;

Fig. 2 is a longitudinal sectional view taken 35 on the line 2—2 of Fig. 1;

Fig. 3 is an enlarged fragmentary sectional view through the block carrying frame taken on the line 3—3 of Fig. 2, and

Fig. 4 is a perspective view of the frame.

40 The hat block consists of sections 1 which are in the form of shells semi-circular in cross section and cooperating to form a hollow body open at its rear end and having a semi-spherical head at its forward end.

45 Therefore, the two sections form a hollow body or block upon which a hat may be placed and since the sections are formed separate from each other they may be adjusted to cause the block to fit snugly within the crown of a 50 hat and thereby firmly hold the hat in

place. In order to carry the block forming sections, I employ a frame which fits into the hollow body and is connected with the companion sections. This frame consists of a hollow carrier 2 having side walls 3 and end walls 4 from which extend side arms 5 and yokes 6 which are of a U-shaped construction and have their bridge portions 7 firmly secured to the sections 1 of the block and their arms 8 slidably engaged with the side arms 5 of the carrier 2. In order to guide sliding movement of the yokes and prevent them from moving out of proper relation to the side arms of the carrier, there has been provided flanges 9 which overlap the side arms of the 60 yoke and allow the yokes to move longitudinally but prevent them from having transverse movement. One arm of each yoke is formed with a longitudinally extending slot 10 to receive a securing screw 11 which is passed through threaded openings formed 65 in a side arm and flange of the carrier, and from an inspection of Fig. 3 it will be seen that by this arrangement the yokes may be moved longitudinally to adjust the block to 70 a proper size and the securing screws then tightened in order to apply pressure which will securely hold the yokes in set positions. It is also desirable to have the yokes urged 75 outwardly so that the block forming sections 80 may move easily away from each other and fit snugly within a hat placed upon the block. In order to do so, there has been provided springs 12 which extend longitudinally of the yokes with their outer ends engaged about pins 13 projecting inwardly from the bridge portions of the yokes and their inner ends engaged about pins 14 projecting outwardly from the upstanding end portions 15 of a bracket 16.

85 In order to rotatably mount the block, I employ a rod or stem 17 which is disposed axially of the block and extends through openings 18 formed in the end walls 4 of the carrier. At one end the stem carries a securing nut 19 and at its other end the stem is flattened to form a head through which passes a bolt 20 which also passes through an opening formed in a flat-sided head at the upper end of a standard 21. This standard 90 95 100

consists of a rod which is slidably received in a bearing or sleeve 22 at the outer end of a bracket 23 and a set screw 24 is employed to securely but releasably retain the standard in 5 a set position. Jaws 25 are formed at the other end of the bracket to straddle a table top or similar support and a set screw 26 is passed through one jaw to engage the table top and firmly secure the bracket. Grooves 10 21' are formed in the standard and constitute seats to receive the set screw, whereby the standard may be secured at a desired height but permitted to be turned in the bearing and allow the block to be swung to a convenient position.

When the hat block is in use, the bracket is secured to a table or other support and by 20 loosening the set screw 24 the standard may be adjusted vertically. After the standard has been properly adjusted, the set screw is again tightened and the stem 17 may also be 25 adjusted by loosening the bolt 20. The hat to be trimmed is placed upon the block in the usual manner and if it is found that the block is not of the proper diameter it is merely necessary to release the set screws 11 and the sections 1 of the block may be moved toward or away from each other until they will 30 properly engage within the crown of the hat. By this arrangement a hat may be supported at such a height and at such an angle that it may be very easily trimmed and as the trimming is applied the block may be rotated about the stem so that all portions of the hat 35 may be presented toward the person trimming the hat and the work very easily and quickly performed.

Having thus described the invention, I claim:

40 1. A hat block comprising companion sections constituting a hat-receiving body and movable towards and away from each other, a frame connecting said sections disposed within the body and consisting of a carrier and yokes slidably connected therewith and secured to the sections of said body, resilient means urging said yokes outwardly to separate said sections, means to releasably secure the yokes and retain the sections in set positions and a stem extending through said carrier to rotatably mount the same and adapted to be secured to a support.

55 2. A hat block comprising companion sections constituting a hat-receiving body and movable towards and away from each other, a frame connecting said sections disposed within the body and consisting of a carrier and yokes slidably connected therewith and having their outer ends secured to the sections of said body, the carrier consisting of a body having side arms at its ends and the arms having side flanges forming longitudinally extending tracks, said yokes being each 60 U-shaped with their bridge portions secured to said sections and their arms extending in-

wardly and slidably engaged in said tracks, means engaging the arms of said yokes to releasably secure the yokes in set positions, springs to urge said yokes outwardly, and a stem extending longitudinally through the 70 carrier and rotatably mounting said frame.

3. A hat block comprising companion sections constituting a hat-receiving body, a frame connecting said sections disposed within the body and consisting of a carrier and 75 yokes slidably carried thereby, said carrier having end walls and side walls connecting the same, arms extending from said end walls, the yokes being secured to said body sections and having arms slidably engaged with the 80 arms of said carrier, means to releasably secure the yokes in set positions, and a stem rotatably supporting said carrier.

4. A hat block comprising companion sections constituting a hat-receiving body, a 85 frame connecting said sections disposed within the body and consisting of a carrier and yokes slidably carried thereby, said carrier having end walls and side walls connecting the same, arms extending from said end walls, 90 the yokes being secured to said body sections and having arms slidably engaged with the arms of said carrier, means to releasably secure the yokes in set positions, a bracket secured between the side walls of said carrier, pins extending from said bracket and the outer portions of said yokes, springs extending between and engaged with said pins and yieldably urging the yokes outwardly to 95 separate the body sections, and a stem to rotatably mount said frame extending longitudinally through the carrier and rotatably received in openings in the end walls thereof.

5. A hat block comprising companion sections constituting a hat-receiving body, a 105 frame connecting said sections disposed within the body and consisting of a carrier and yokes slidably carried thereby, said carrier having end walls and side walls connecting the same, arms extending from said end walls and formed with longitudinally extending side flanges, the yokes being secured to the body sections and having arms slidably fitting beneath the flanges, set screws passed through said flanges and engaging the arms of the 110 yokes to releasably secure the yokes in set positions, and a stem rotatably supporting 115 said carrier.

6. A hat block comprising companion sections constituting a hat-receiving body, a 120 frame connecting said sections disposed within the body and consisting of a carrier and yokes secured to said body sections and having arms slidably engaged with said carrier, means to releasably secure the yokes in set 125 positions relative to the carrier, and a stem rotatably supporting said carrier.

7. A hat block comprising companion sections constituting a hat-receiving body, a 130 frame connecting said sections disposed

within the body and consisting of a carrier and yokes, said carrier having end walls and side walls connecting the same and formed with flanges extending longitudinally of the end walls, the yokes being secured to the body sections and having arms slidably fitting beneath the flanges, set screws passed through

said flanges and engaging the arms of the yokes to releasably secure the yokes in set positions and a stem rotatably supporting said 10 carrier.

In testimony whereof I affix my signature.

AGUSTIN JIMÉNEZ. [L.S.]
